UNITED STATES PATENT OFFICE.

DWIGIIT S. RICHARDSON, OF NEW YORK, N. Y.

DESIGN FOR A FIRE-POT.

SPECIFICATION forming part of Design No. 33,039, dated July 31, 1900.

Application filed June 28, 1900. Serial No. 21,940. Term of patent 14 years.

To all whom it may concern:

Be it known that I, DWIGHTS. RICHARDSON, of New York, county of New York, and State of New York, have invented and produced a new and original Design for Fire-Pots, of which the following is a specification, reference being had to the accompanying drawing, forming a part of the same.

The figure of the drawing represents in perspective a fire-pot embodying the present design.

The leading or characteristic feature of the design is the circular body portion of the fire-pot, slightly tapered from top to bottom and having the outwardly-curved projection extending beyond the general contour at the top thereof.

The letter A indicates the body portion of

the fire-pot, slightly tapered from top to bottom. C indicates an outwardly and upwardly extending flange at the top, and D outwardly-curved projections merging into the upper edge of the body portion and the flange C. These projections D taper toward the bottom and merge gradually into the body portion and flange. Thus the flange has the appearance of a continuous flange around the top of the fire-pot with outwardly-extending curved projections.

I claim—

The design for a fire-pot herein described and shown.

DWIGIIT S. RICHARDSON.
